TABLE CONSTRUCTION

Application filed March 14, 1929. Serial No. 347,005.

The present invention relates to improvements in the construction of tables having extensible top sections.

An important object of the invention is the provision of a support slide whereby the extensible top sections of a table may be conveniently and noiselessly adjusted.

A further object of the invention is the provision of a table embodying an adjustable support slide construction designed to operate smoothly and without obstruction.

Another object of the invention is the provision of a table having adjustable top sections constructed so that the complementary bars forming the flexible portion of the top will be attached to a flexible connecting member in a novel manner designed to obviate distortion of the complementary bars.

Still another object of the invention is to improve the general construction of tables of the above character so as to simplify the construction thereof and improve the operation of the movable elements.

Other objects and advantages of the invention will become apparent as the description progresses.

In the accompanying drawing forming a part of this specification and in which like reference characters are employed to designate corresponding parts throughout the same:

Figure 1 is a perspective view of the improved table showing the top sections in retracted positions,

Figure 2 is a similar view showing the top sections in extended positions,

Figure 3 is a bottom plan view of the table,

Figure 4 is an enlarged transverse section taken on the line 4—4 of Figure 3,

Figure 5 is an enlarged fragmentary longitudinal section through the table,

Figure 6 is a longitudinal section taken on the line 6—6 of Figure 5, and

Figure 7 is a section taken on the line 7—7 of Figure 5.

Referring to the drawing, wherein for the purpose of illustration is shown a preferred embodiment of the invention, the numeral 10 generally designates a rigid table frame sup-

ported on legs 11 and embodying longitudinal side rails 12. Rigidly supported in a transverse position on the frame is a fixed top section 13 disposed centrally between a pair of horizontally and longitudinally adjustable top sections 14.

The movable or adjustable top sections 14 embody a rigid portion 15 and an inner flexible portion 16. The united portions 15 and 16 are mounted on the frame so as to slide between the frame side rails 12, the rigid portion being limited to movement in a horizontal plane while the flexible portion is arranged to roll about a pair of guide rollers 17 when the top sections are retracted.

An essential feature of the present invention resides in the provision of suitable slide structures adapted to adjustably support each section and arranged adjacent each side of the section, as shown to advantage in Figure 3. To accommodate the slide construction, the inner surface of each frame rail 12 is formed with a longitudinally directed slot 18 disposed between the centre and outer end of the rail, as shown in Figure 6. Attached to the under side of the rigid portion of each top section 14 are interior rails 19 mounted parallel with the frame rails and spaced inwardly therefrom. Each of the rails 19, carried by the top sections, is formed with a longitudinal groove 20 arranged adjacent the outer end of the rail. Adjacent their inner ends, the rails 19 support channel shaped brackets 21 having the web portion secured to the inner face of the rail and the flanges extending laterally outward therefrom. A complementary channel shaped bracket 22 is secured to the inner face of the frame rail 12 adjacent the outer end thereof, this bracket being disposed in horizontal alignment with and diagonally opposed to the bracket 21.

Slidably positioned between the co-operating rail 19 and the frame rail 12 is a longitudinal slide bar 23 of elongated, rectangular cross section formed to slide within the guide brackets 21 and 22. Adjacent its forward end, the slide bar 23 carries a lateral, outwardly projecting tongue 24 disposed to slidably project within the longitudinal groove 190

18. At the opposed end, the slide bar carries a laterally and inwardly projecting tongue 25 arranged to slidably project within the longitudinal groove 20. Adjacent its outer end, the slide bar 23 carries an angular bracket 23' having one leg attached to the lower edge of the slide and formed so that an angular upright leg will be bent to slidably embrace the lower edge portion of the rail 19. 10 This slide construction will permit easy and unrestricted adjustment of the extensible top sections within their limited movements.

The flexible portion 16 of each top section is composed of a plurality of longitudinal slats or bars 26 arranged transversely and united by a pair of longitudinal flexible strips 27, preferably formed of canvas or similar material. The forward ends of the canvas strips 27 are attached to the inner end portion 20 of the rigid portion 15 so as to connect the flexible portion therewith. Heretofore, the flexible strips 27 have been connected to the slats 26 by placing the strips in contact with the under side of the slats and attaching the same thereto through the medium of an auxiliary connecting strip which was nailed or otherwise connected with the slat. This construction was found objectionable in that the slats and connecting strips, being usually 30 formed of wood, became disconnected due to the distortion or warping of the attached members. In the present construction, the slats 26 are of greater thickness and have relatively narrow slots formed therethrough 35 designed to accommodate the canvas strips 27 which are then connected to the slots by tacks 28 or similar securing elements. Thus, the slats are composed of a unitary bar of wood which, if distorted, will have a uniform distortion throughout its length. 40

It is to be understood that the form of our invention herein shown and described is to be taken as a preferred example of the same, and that various changes as to the shape, size, and 45 arrangement of parts may be resorted to without departing from the spirit of the invention or the scope of the subjoined claim.

Having thus described our invention, we claim:

50 In a table including a stationary support frame and a slidably adjustable top section, a pair of slide bars disposed longitudinally between the rails of the frame and adjustable top section, a tongue attached to and projecting outwardly from the forward portion of each slide bar and projecting within a longitudinal guide groove in the rail of the table frame, a complementary tongue formed adjacent the outer ends of the slide bars and projecting inwardly to engage longitudinal grooves formed in the rails attached to the 60 slidably top section, and guide brackets attached in diagonally opposed positions to the 65 rails of the table frame and top section dis-

posed to guide the slide bars and retain the same in a horizontal plane.

In witness whereof we have hereunto set our hands.

NAPOLEON GIARD. 70
HENRY O. GIRARD.
